CLAIM

I claim the ornamental design for a basket end tip for vitrification stick, as shown and described.

DESCRIPTION

FIG. 1 is a top plan view of a basket end tip for vitrification stick showing my new design with an exemplary cap in a closed position;

FIG. 2 is a cross-sectional view taken along line 2-2 in FIG. 1;

FIG. 3 is a top plan view of the basket end tip for vitrification stick with the exemplary cap in an open position;

FIG. 4 is a bottom plan view thereof;

FIG. 5 is a right side view thereof, the left side view being a mirror image thereof;

FIG. 6 is a top front perspective view thereof;

FIG. 7 is a cross-sectional view taken along line 7-7 in FIG. 3;

FIG. 8 is a close up view of the basket end tip for vitrification stick from FIG. 3;

FIG. 9 is a close up view of the basket end tip for vitrification stick from FIG. 6;

FIG. 10 is a close up view of the basket end tip for vitrification stick from FIG. 7;

FIG. 11 is a top front perspective view of a second embodiment of the basket end tip for vitrification stick having transparency; and,

FIG. 12 is a close up view of the second embodiment of the basket end tip for vitrification stick from FIG. 11.

The broken lines are included for the purpose of showing the environmental structure and form no part of the claimed design.

The rear view of the vitrification stick forms no part of the claimed design and is omitted.

Except for the transparency of the second embodiment of the claimed design illustrated in FIGS. 11 and 12, all other aspects of the second embodiment of the claimed design are the same as the first embodiment of the claimed design illustrated in FIGS. 1-10.
